UNITED STATES PATENT OFFICE.

PHILIP P. MERRILL, OF EVANSTON, ILLINOIS, ASSIGNOR TO LUDLOW TYPOGRAPH COMPANY, OF CHICAGO, ILLINOIS, A CORPORATION OF ILLINOIS.

PRINTING ART.

Application filed February 16, 1924. Serial No. 693,255.

My invention in its broadest aspect relates to the production of printing-face-equipped bodies in general, but more particularly to so-called line-cast slugs each comprising a shank portion which, in accordance with common practice, is cast in a mold provided as one member, and a head-portion, either continuous or interrupted, and presenting a printing-face portion or portions comprising such printing characters as letters, numerals and rule-form elements, and, according to common practice, cast integral with the shank portion and into matrices provided as members separated from the shank-mold member and positioned in alignment with each other at the open side of the mold cavity of the shank-mold member.

My invention further relates to the aligning, either crosswise or lengthwise of the printing-face-equipped bodies, of the printing faces of such bodies when grouped together to present the printing form; and more especially, to the alignment of such faces in a direction crosswise of such bodies, as, for example, in the case of printing bodies for printing "blank forms" and office and factory forms comprising parallel rule lines extending in one direction only, or intersecting parallel rule lines, and in the case of tabular work comprising lines, or columns, of single letters, words or numerals, in all of which cases the accurate alignment of the printing faces of adjacent printing bodies is necessary to produce high grade work.

As printing-face bodies have been provided hitherto, non-alignment of the printing faces thereon, when such bodies are grouped together to comprise the "form", has been practically inevitable, and this is especially the case with the above-referred-to line-cast slugs which, in the making up of a printing form, are grouped together, in flatwise relation, in a frame, and where failure to accurately align the ends of the slugs, as, for example, through carelessness or lack of skill, occurs, the printing faces on adjacent slugs are out of alignment, with the above-referred-to disadvantage. Furthermore, the head portions of line-cast slugs, as commonly manufactured, are sometimes offset relative to the shank portions thereof, in a direction lengthwise of the slug, due to non-alignment of the shank mold cavity and the matrices, and when this occurs either

non-uniformly, or as to certain only of the line-cast slugs to be grouped to comprise the printing form, it is impossible, from a practical standpoint, regardless of the care and skill exercised by the one producing a printing form therefrom, in case such form is made up manually, to effect alignment of printing faces on adjacent slugs. 60

My primary object is to overcome the objections above referred to, to the end that alignment of the printing faces on adjacent printing bodies, especially in the case of line-cast slugs, will be insured, and without requiring skill or a painstaking operation and regardless of the non-alignment of the 70 head portions of the slugs relative to the shank portions thereof.

I have chosen to illustrate my invention in connection with the producing of line-cast slugs for the composing of forms from which blanks having intersecting rule lines are to be printed, and also in connection with line-cast slugs for the composing of forms from which blanks having rule lines extending in one direction only are to be 80 printed, but without intending to limit my invention thereto.

Referring to the accompanying drawings, wherein Figures 1 to 9, inclusive, relate to the forming of a line-cast slug the head portion of which is continuous, and Figures 10 and 11 to a slug the head portion of which is interrupted:—

Figure 1 is a perspective view of a mold-member in which the shank portion of the line-cast slug is formed, and a matrix-composing stick containing a series of matrices in which the head portion of the slug is cast, the shank and head-forming portions referred to being shown in separated condition. Figure 2 is a section taken through the assembled members of Fig. 1, these two views being somewhat diagrammatic, with certain parts of the structure with which they are associated in common practice, 90 omitted, sufficient only of the structure being shown to illustrate the application of my invention. Figures 3, 4 and 5 are perspective views, Figs. 4 and 5 being broken views, representing different kinds of matrices 100 which are employed in the casting of the slugs for producing the printed ruled blanks, composed of intersecting rule-lines, above referred to. Figure 6 is a plan view of a plurality of the slugs produced by the structure. 110

ture of the preceding figures, these slugs being grouped together into the relative positions occupied by them in the composing of the printing form. Figure 7 is a view in side elevation of the upper portion of one of the similar slugs of Fig. 6. Figure 8 is a perspective view of the grouped slugs of Fig. 6. Figure 9 is a broken, perspective, view of the central upper portion of any one of the slugs above referred to, the slug being viewed from the side opposite to that shown in Fig. 7. Figure 10 is a plan view of a printing-face-equipped slug in accordance with my invention, to be grouped with similar slugs for the printing of blanks composed of rule-lines extending in the same direction, the slug shown being of a type wherein the portions thereof presenting the printing faces, and comprising the interrupted head of the slug, are wider than the shank-portion of the slug; and Figure 11, a perspective view, with a portion partly broken away, of a pair of the slugs of Fig. 10 in assembled position with a filler-slug interposed therebetween.

As a preface to the following description it may be stated that, as machines are commonly provided for producing line-cast slugs the shank-mold portion and the matrices are separate, the shank mold portion being provided on the machine and associated with means for discharging into its mold cavity and into, and against, the matrices, molten metal to form the slug, and the matrices being grouped together in a matrix-composing stick adapted to be positioned on the machine to close the side of the shank-mold and present the mold cavities in the matrices to the metal introduced into the shank mold. Machines of this type being well-known in the art, detailed showing thereof is omitted, only such portions of the machine as are necessary to an understanding of my invention being illustrated. Accordingly a shank-mold member is illustrated somewhat diagrammatically, however, at 10, the mold cavity therein and in which the shank portion of the slug is cast, being shown at 11. This mold cavity opens through the upper surface of the member 10 and receives through its ported under-surface, represented at 12, the molten slug metal from which the shank and head of the slug are to be formed. A matrix-composing stick is represented at 13, the central opening 14 therein receiving the matrices, represented at 15 shown as formed of the body portions 16, which extend into the opening 14, and the lugs 17 which seat upon the upper surface of the stick 13, the matrices 15, assembled with the stick 13, being held in place therein by a clamping, follower, block 18 cooperating with a clamping screw 19 having threaded engagement with an end portion of the stick 13.

The matrices 15 are provided with mold cavities of a contour, or contours, as the case may be, for producing the desired printing face on the line-cast slug to be produced. The particular form of slug shown in Figs. 1 to 9 inclusive at 20 and embodying my invention, is provided for producing blank ruled forms comprising intersecting rule lines, the rule faces on the slugs for printing the horizontal and vertical rule lines being represented at 21 and 22, respectively, these rule faces being provided on, and as a part of, the head portions 23 of the slugs, the shank portions of which are represented at 24. Three kinds of matrices, shown in Figs. 3, 4 and 5, are employed in the producing of the slugs 20. The matrices of the form shown in Figs. 3 and 4 are provided for producing portions of the single horizontal rule faces 21 which extend lengthwise of the slug, and the matrices of the form shown in Fig. 5 are provided for producing the remaining portions of the single rule faces 21 and also the rule faces 22 intersecting therewith, these last-referred-to rule faces being the ones which it is desired be accurately aligned in the composing of the printing form from a plurality of the slugs.

In accordance with my invention the line-cast slugs are provided with means, preferably of an interlocking character, for insuring such relative positioning of the slugs in grouped relation, that accurate alignment of the printing faces thereon in a direction crosswise of the slugs will be insured. Referring to Figs. 6 to 9 inclusive the particular illustrated form of such means is of the lug and socket type, each line-cast slug being provided with a lug, represented at 25, extending from one face thereof, and with a boss 26 containing a laterally-opening socket 27, these lugs and sockets being located exactly in the same position lengthwise and crosswise of the slug. In the particular construction shown the positioning means referred to are provided above the shank portion of the slug on the head portion thereof, these parts being preferably formed by casting the metal forming the head portion into matrices of such contour as to produce the lugs and socketed bosses referred to. To this end the mold cavity of the matrix of Fig. 3 is so shaped as not only to produce the rule face 21, as above described, but also to produce the lug and socketed boss, the portions of the mold cavity by which the lug and boss are produced being indicated at 28 and 29.

In the composing of a printing form from the line-cast slugs shown, the slugs are grouped together, or assembled, as represented in Figs. 6 and 8, in which position the lugs 25 extend into, and closely fit, the sockets 27 of adjacent slugs. As the lugs and sockets occupy the same position on each

slug, relative to the rule faces 22, the positioning of the slugs as stated insures accurate alignment of these rule faces to produce perfectly straight, unbroken, rule faces in the printing form, and it is thus immaterial, so far as the aligning of the rule faces 22 is concerned, whether or not the head portions of the slugs accurately align with the shank portions thereof. In effect the side 10 walls of the sockets 27 and the surfaces of the lugs co-operating therewith, as above stated, form cooperating stop surfaces by which the slugs in the operation of assembling them, are caused to become positioned 15 relative to each other for effecting the desired alignment of the printing-faces thereof. In this connection it may be stated that under certain conditions satisfactory results may be produced by providing single stop 20 portions on opposing surfaces of the slugs.

Referring to the structure shown in Figs. 10 and 11, which embodies my invention in its application to the production of slugs having printing faces which extend crosswise only of the slugs, in which case the head portion of the slug may be, and as shown is, interrupted, with the printing faces extending laterally beyond the face of the shank, the shank portion of the slug is represented at 28 and the printing face portions at 29, the portions 29 with the interlocking means hereinafter referred to, forming the head of the slug, and extending equidistantly laterally beyond the opposite faces of the shank 28, as shown. The interlocking devices for the slugs, shown as comprising the lug and socket portions 30 and 31, as explained of the structure of the preceding figures, are of such form that the lug 30 30 extends outwardly beyond the adjacent ends of the printing-face portions 29 and the socket of the portion 31 extends inwardly relative to the other ends of the portions 29, as shown, whereby when a plurality of the slugs 28 are grouped together as shown in Fig. 11, the lugs 30 will enter the sockets 31 of adjacent slugs 28 and interlock the slugs as explained of the other structure.

In the producing of the slug now being described, the same general character of devices may be used, and the same operations may be practiced, as explained of the structure of the preceding figures. In this case the mold cavities instead of being relatively narrow, would be relatively wide and extend beyond the side of the shank-mold cavity, blank matrices would be interposed between the printing-face-forming matrices to form the interruptions in the head portion of the slug and the lug and socket-forming matrices would be without printing-face-forming mold cavities; however, the lug and socket-forming mold cavities being grouped in a mold member with the matrices forming the printing-face portions of the slugs, the lugs

and sockets 30 and 31 bear a fixed relation to the printing faces of the slug as they do in the case of the slug of the preceding figures, wherein the head is continuous, whereby the printing-faces on adjacent slugs are caused to accurately align.

Where the slugs are formed with the overhanging, or laterally projecting, head portion 29, as explained, and it will be understood that this feature may be incorporated in a slug of the continuous-head type, if desired, filler, blank, slugs, as for example of the form represented at 32 and shown as unprovided with heads, would be interposed between adjacent ones of the slugs 28 to fill the space therebetween, while permitting endwise abutting of aligned printing-face portions.

While I have illustrated and described my invention as applied to the production of certain forms of printing-face-equipped bodies, I do not wish to be understood as intending to limit it thereto nor to the particular printing-faces shown, as the invention may be employed in the production of various other forms of printing-face-equipped bodies and various other printing-faces where it is desired that alignment of printing-faces on adjacent printing-face-equipped bodies be effected.

What I claim as new, and desire to secure by Letters Patent, is:

1. In the art of molding printing-face-equipped bodies, molding thereon simultaneously with the molding of the printing faces, stop portions in such relation that upon the assembling of such bodies with said stop portions in engagement with each other, printing faces on said bodies align in a plane crosswise of said bodies.

2. In the art of molding printing-face-equipped bodies, molding thereon simultaneously with the molding of the printing faces, stop portions on opposite sides of each body and in such relation that upon the assembling of such bodies with said stop portions in engagement with each other, printing faces on said bodies align in a plane crosswise of said bodies.

3. In the art of molding printing-face-equipped bodies, positioning a printing-face, a stop-forming mold and a shank-forming mold in communication with each other and introducing molten metal into both molds thereby to mold on such bodies, simultaneously with the molding of the printing faces, stop portions in such relation that upon the assembling of such bodies with said stop portions in engagement with each other, printing faces on said bodies align in a plane crosswise of said bodies.

4. In the art of forming a printing-face-equipped body comprising a shank portion having a printing-face-equipped head integral therewith, molding said body to cast

simultaneously thereon in a position above the shank portion, a printing face and an aligning stop portion, the latter for engagement with an aligning stop portion on an adjacent printing-face-equipped body when said bodies are assembled with the printing faces thereon in alignment in a plane crosswise of said bodies.

5. In the art of forming a printing-face-equipped body comprising a shank portion having a printing-face-equipped head integral therewith, molding said body to cast simultaneously on its head, a printing face and an aligning stop portion, the latter for engagement with a stop portion on an adjacent printing-face-equipped body when said bodies are assembled with the printing faces thereon in alignment in a plane crosswise of said bodies.

6. In the art of forming a printing-face-equipped body comprising a shank portion having a printing-face-equipped continuous head integral therewith, molding said body to cast simultaneously on said head, a printing face and an aligning stop portion, the latter for engagement with an aligning stop portion on an adjacent printing-face-equipped body when said bodies are assembled with the printing faces thereon in alignment in a plane crosswise of said bodies.

7. In the art of forming a printing-face-equipped body having integral shank and printing-face-equipped head portions, molding the shank and head portions in shank and head forming members, respectively, and in the molding operation forming on the head of the printing face and stop-portions the latter in such relation that when engaged with stop-portions on adjacent printing-face-equipped bodies, upon assembling said bodies, printing faces thereon will extend in alignment within a plane crosswise of said bodies.

8. In the art of forming a printing-face-equipped body having a shank and a continuous head on, and integral with, said shank, molding the shank portion and the continuous head portion in shank and head-forming portions, respectively, and in the molding operation forming on the continuous head the printing face and integral therewith stop portions the latter in such

relation that when engaged with stop portions on adjacent printing-face-equipped bodies, upon assembling said bodies, printing faces thereon will extend in alignment within a plane crosswise of said bodies.

9. In the art of forming a printing-face-equipped body having a shank portion and a printing-face-equipped head integral therewith, simultaneously molding on said body printing faces and stop portions the latter positioned above the shank portion at opposite surfaces of said body for engagement with stop portions on adjacent printing-face-equipped bodies when said bodies are assembled with the printing faces thereon in alignment in a plane crosswise of said bodies.

10. The method of producing alignment of printing faces on printing-face-equipped bodies in a plane crosswise of the bodies, which consists in simultaneously molding on the bodies the printing faces and stop portions the latter on juxtaposed ones of said bodies and so disposed that upon the assembling of said bodies said stop portions directly engage with each other and produce such alignment, and thereafter assembling said bodies into such engaging position.

11. The method of producing alignment of printing faces on flatwise-opposed printing-face-equipped slugs a plane crosswise of the slugs, which consists in simultaneously molding on the slugs the printing faces and stop portions the latter extending transversely of said slugs and so disposed that upon the assembly of said slugs said adjustment stop portions directly engage with each other and produce such alignment, and thereafter assembling said bodies into such engaging position.

12. In the art of molding printing-face-equipped bodies, molding in succession a plurality of bodies in a mold shaped to form a body having a printing face and stop portions at opposite sides thereof, the latter in such relation that upon assembling a plurality of such bodies with said stop portions in engagement with each other, printing faces on said bodies align in a plane crosswise of said body.

PHILIP P. MERRILL.
